KARL A. SODERSTROM, OF PHILADELPHIA, PENNSYLVANIA.

REGENERATIVE FURNACE AND METHOD OF FIRING FURNACES.

Application filed May 23, 1923. Serial No. 640,822.

To all whom it may concern:

Be it known that I, KARL A. SODERSTROM, a citizen of the United States, residing at Philadelphia, county of Philadelphia, and 55 State of Pennsylvania, have invented a new and useful Improvement in Regenerative Furnaces and Methods of Firing Furnaces, of which the following is a full, clear, and exact description, reference being had to 10 the accompanying drawings, which form a part of this specification.

This invention relates to an improvement in open hearth regenerative furnaces and the method of firing such furnaces.

One of the objects of my invention is 15 to provide a furnace of this type in which the air for supporting combustion is heated by direct contact with the outgoing products of combustion, and thereby partially 20 heating the air and reducing the temperature of the waste gases.

Another object of my invention is to 25 accelerate the speed of the outgoing waste gases by direct contact with the ingoing air, thus quickly drawing the spent gases from the combustion chamber and thereby increasing the temperature of the hearth or combustion chamber, and as the force 30 of the ingoing air is under the direct control of the furnace man, the temperature of the furnace can readily be controlled.

Another object of my invention is to 35 rapidly extract heat from the roof of the combustion chamber by the ingoing air and thereby increase the life thereof and at the same time increase the temperature of the ingoing air.

A further object of my invention is to 40 utilize some of the waste products of combustion for atomizing and injecting the fuel into the combustion chamber, which enables me to prevent premature ignition and control subsequent combustion by reason of lowered oxygen content of the atomizing agent.

Another object of my invention is to 45 provide means for varying the heating of the opposite sides of the hearth or combustion chamber, so that the temperature of the bath on different sides of the hearth can 50 be controlled by the furnace man.

The precise nature of my invention will be best understood by reference to the ac-

companying drawings, it being premised, however, that various changes may be made in the details of construction without departing from the spirit and scope of my invention as defined in the appended claims.

Fig. 1 is a vertical longitudinal section through one form of furnace built in accordance with my invention, on the line 1—1 of Fig. 2.

Fig. 2 is a horizontal section on line 2—2 of Fig. 1.

Fig. 3 is a similar view on the line 3—3 of Fig. 1.

Fig. 4 is a vertical transverse section on line 4—4 of Fig. 1, looking toward the combustion chamber.

Fig. 5 is a vertical section on the line 5—5 of Fig. 2.

Fig. 6 is also a sectional view on the line 4—4 of Fig. 1, looking toward the flues leading from the combustion chamber.

Referring to the accompanying drawings, 75 10 designates the combustion chamber above the hearth 11 and below the roof 12. Located between the roof 12 of the combustion chamber and the main roof 13 is a regenerator chamber. The regenerator chamber is divided into two chambers 14 80 and 15 by a central wall 16, while these chambers 14 and 15 are divided by walls 17 and 18, respectively.

Between the walls 17 and 18 and the side walls of the furnace are flues 19 and 20, 85 respectively, for the outgoing gases or products of combustion. The flue 19 communicates with a downtake flue 21, while the flue 20 communicates with a similar flue 22. The flues 21 and 22 communicate with 90 the transverse main or offtake flue 23, which may lead to a stack or some point where the heat in the products of combustion is utilized for heating purposes.

Located between the central wall 16 and 95 walls 17 and 18 are air passages 24 and 25, respectively, which communicate with a downwardly and reversely extending passage 26, the mouth of which communicates with the combustion chamber 10.

Extending laterally from the flues 21 and 22 and communicating with the combustion chamber 10 above passage 26 are passages 27 and 28. 29 and 30 are dampers in passages

27 and 28, respectively, for controlling the flow through said passages, and located in flues 21 and 22 are baffles 31 and 32, respectively, for directing some of the products 5 of combustion from flues 21 and 22 into passages 27 and 28. The central wall 16 is chambered between air passages 24 and 25 and extending downwardly in this space is 10 a main fuel feed pipe 33, having branches 34 and 35 extending into passages 27 and 28, respectively, and are arranged to feed powdered fuel to said passages. 35^a is a control handle extending from a deflector plate in pipe 33. The passages 26, 27 and 15 28 do not communicate directly with the combustion chamber, but open into a common port 36, which is directly in communication with the front end of the combustion chamber. The rear end of the combustion 20 chamber is in communication with two off-take flues 38 and 39, the upper ends of which communicate with what I term the front end of the regenerator chamber above the rear end of the combustion chamber, 25 and an arch-shaped water-cooled nose 36^a at the mouth of port 36.

40 are doors closing clean-out openings communicating with flues 38 and 39.

41 is a tap-out opening through one of 30 the side walls of the furnace, and 42 is a runner for the metal extending from said opening. The side walls of the furnace are also provided with a plurality of charging and working openings 43 which are provided 35 with the usual closures.

44 and 45 are openings in the upper portions of the front walls of flues 38 and 39, respectively.

46 and 47 are nozzles for directing the air 40 for supporting combustion into the regenerator chamber through openings 44 and 45, and are supplied with air by a blower 48 through pipe 49. The pipe 49 is provided with a deflector plate having a handle 45 50, and is arranged to equally divide the air passing through pipe 49 to the nozzles, or to direct more air to one nozzle than the other.

The downtake portion of air passage 26 50 is provided with a removable hood 51, while the downtakes 21 and 22 are provided with similar hoods 52. These hoods can readily be removed so that the passages can be quickly cooled and provide ready access for 55 cleaning and inspecting the various passages, while the doors 40 in flues 38 and 39 provide means for readily cooling said passages and for removing slag which has been carried over from the hearth.

60 Assuming that the furnace is charged and in operation, the firing is carried on in the following manner.

Pulverized coal or other fuel is fed in a continuous manner at a predetermined rate 65 to pipe 33, from which it is fed to passages

27 and 28, dampers 29 and 30 being open to the proper extent. Jets of air are delivered to the regenerator chamber from nozzles 46 and 47, the air from blower 48 being delivered at the proper speed to cause the air to enter openings 44 and 45 at the required velocity.

The air jets from nozzles 46 and 47 pass directly through the products of combustion rising through flues 38 and 39 from the combustion chamber 10. These air jets are directed toward each other and in a downward direction toward the roof 13, but do not meet each other, as the point at which they would meet is slightly beyond the front of wall 16. These jets of air increase by suction the flow of the spent gases or products of combustion from the combustion chamber in proportion to their velocity, which velocity is somewhat reduced by the passage of the streams of air through the spent gases. During the passage of these streams of air through the rising spent gases, the temperature of the gases is reduced while the streams of air will be raised in temperature by radiation and convection. As the velocity of the streams of air is very high, the streams will not be broken up to any detrimental extent (for example, before its object is accomplished) by their passage through the gases. These streams of air are directed downward against the hottest portion of the roof 12 and are further heated by contact therewith, and then pass into passages 24 and 25 from which the two streams

pass into passage 26, from which they pass into combustion chamber 10. The partially cooled gases from flues 38 and 39 are frictionally carried by the air streams through chambers 14 and 15 between the streams of air and the side walls of the furnace, and pass into flues 19 and 20 at a fairly high velocity. These streams of spent gases pass from flues 19 and 20 into the respective flues 21 and 22. These streams of spent gases in flues 21 and 22 are split up by baffles 31 and 32. A portion of the stream in flue 21 is directed to passage 27 by baffle 31, while a portion of the stream in flue 32 is directed into flue 22 by baffle 32.

The velocity of the streams of spent gases or products of combustion passing through passages 27 and 28 is sufficient to atomize and carry the fuel delivered thereto into the combustion chamber where it is thoroughly mixed with the stream of air from passage 26.

As the spent gases which carry the fuel into the combustion chamber and the fuel do not form a combustible mixture, combustion does not take place until a mixture is formed with the air at the entrance of combustion chamber 10, and combustion cannot take place in the fuel or air delivery ports. The remainder of the spent

gases passing down flues 21 and 22 enters the flue 23, leading to a stack or a waste heat utilizing apparatus in which the remaining heat may be extracted and commercially used.

If it is desired to apply a greater heat to one side of the furnace than to the other, the deflector plates in air pipe 49 and fuel pipe 33 are positioned to direct a greater amount of air and fuel to the side which is to be heated to the greatest extent.

It will also readily be understood that the temperature of the furnace can be raised or lowered by varying the velocity of the air and the feed of the fuel and the percentage of oxygen content of the mixture.

As the roof 13 is of arcuate form over the uptake flues 38 and 39 as well as over the regenerator chamber, the heat therefrom will be radiated toward the jets of air first passing through the spent gases and then along the two streams of spent gases passing to flues 19 and 20.

The advantages of my invention result from the provision of a regenerative furnace of initial low cost, and in which the ingoing air is partially heated by the outgoing spent gases, as well as a furnace in which the roof of the combustion chamber is cooled by streams of air traveling at a high velocity impinged against said roof, thereby rapidly extracting the heat from said roof, whereby the life of the furnace is greatly increased over that of a furnace over whose roof the air flows at a slow speed.

Another advantage results from the provision of a regenerative furnace in which the air is heated without the use of the usual checker work, or two sets of chambers with reversing valves, and thereby eliminate the cost for cleaning the checker work, cost of supplying water for cooling the valves, as well as the loss of heat carried off by the cooling water.

A further advantage results from the provision of a furnace in which the various flues and passages are relatively short, so that I am enabled to provide hoods and doors at or near one of the turns, whereby the flues and passages can be quickly cooled, inspected, and cleaned.

Another advantage results from the provision of a furnace from which the speed of the outgoing gases from the combustion chamber is accelerated by suction generated by the ingoing air, so that the combustion chamber is maintained at a high temperature.

A still further advantage results from the provision of a furnace in which the fuel is carried into the combustion chamber by a non-combustible gas, so that ignition does not take place until the fuel has entered the

combustion chamber and with a flame development under control.

Another advantage results from the provision of a furnace in which I am enabled to carry out a method of firing in which the ingoing air is partially heated by passing through the outgoing spent gases, and whereby I am enabled to cause the outgoing gases to travel at a sufficient velocity so that a portion of the spent gases can be directed back to the combustion chamber to carry the fuel into the combustion chamber, so that ignition, or a mixture of the fuel and air, is not made until the fuel passes well beyond the mouth of the fuel delivery port.

Having now fully described my invention, what I claim and desire to protect by Letters Patent is:

1. The method of firing a furnace, comprising the step of forcing the air for supporting combustion in contact with the outgoing products of combustion to heat the air and propelling the air at such a velocity that the stream of air will not be substantially broken up, separating substantially all of the stream of air from the products of combustion after contact therewith, conducting the separated stream of air into the combustion space of the furnace, and forcing fuel into the combustion space to form a combustible mixture with the air.

2. The method of firing a furnace, comprising the step of forcing the air for supporting combustion in contact with the outgoing products of combustion to heat the air and propelling the air at such a velocity that the stream of air will not be substantially broken up, separating substantially all of the stream of air from the products of combustion after contact therewith, conducting the separated stream of air into the combustion space of the furnace, separating a portion of the products of combustion after separation from the air, conducting one portion of said products of combustion out of the furnace, and utilizing the remainder for forcing fuel into the combustion space to form a combustible mixture.

3. The method of firing a furnace, comprising the step of carrying fuel into the combustion space of the furnace by a jet of non-combustible gas and simultaneously directing a current of air to impinge on the roof of the combustion space and thereafter to pass to the combustion space and commingle with the fuel to form a combustible mixture which is ignited by the heat of the furnace.

4. The method of firing a furnace, comprising the step of continuously separating from the outgoing products of combustion a portion thereof and continuously conveying fuel to the combustion space by the

separated portion of products of combustion and simultaneously and continuously directing a current of air to impinge on the roof of the combustion space and thereafter commingle with the products of combustion and fuel within the combustion space of the furnace, and form a combustible mixture therewith.

5. A furnace having a combustion space, an offtake flue for the products of combustion leading therefrom, a regenerator chamber, means for directing a jet of air at a high velocity into the regenerator chamber in contact with the products of combustion to heat the air, means in the regenerator for separating substantially all of the heated air from the products of combustion and for conducting the air to the combustion space, and means for injecting fuel into the combustion space.

6. A furnace having a combustion space, an offtake flue for the products of combustion leading therefrom, a regenerator chamber, means for directing a jet of air at a high velocity into the regenerator chamber in contact with the products of combustion to heat the air, means in the regenerator for separating substantially all of the heated air from the products of combustion and for conducting the air to the combustion space, means for conducting a portion of the products of combustion back to the combustion space, means for feeding fuel into the stream of products of combustion flowing to the combustion space, and means for directing a stream of air into the stream of fuel and products of combustion within the combustion space.

7. A furnace having a combustion chamber, a regenerator chamber, an offtake flue leading from the combustion chamber to the regenerator chamber, means for directing a jet of air into the regenerator chamber in contact with the gases passing from the combustion chamber to the regenerator chamber, an air flue leading from the regenerator chamber to the combustion chamber, an offtake flue leading from the regenerator chamber, means for directing some of the products of combustion from the last flue back to the combustion chamber, and means for feeding fuel into the stream of products of combustion passing back to the combustion chamber.

8. A furnace having a combustion chamber, a regenerator chamber above the combustion chamber, two flues at one end of the furnace for conducting the products of combustion from the combustion chamber to the regenerator chamber, two air nozzles at the said end of the furnace for directing blasts of air into the regenerator chamber through the flues, said nozzles being directed toward each other, a wall in the regenerator chamber dividing the rear end of the regenerator

chamber into two compartments, said wall extending forwardly a sufficient distance to prevent commingling of said air jets, a wall in each compartment, separating the rear of each compartment into an air passage and a flue, a passage for conducting the air from the passages leading from the regenerator compartments to the combustion chamber, a passage communicating with each flue leading from the regenerator compartments and with the combustion chamber, a baffle in each flue for directing a portion of the outgoing products of combustion into said last mentioned passages, and means for feeding fuel to said last mentioned passage and into the paths of the streams of products of combustion flowing back to the combustion chamber.

9. A furnace having a combustion space, an offtake for the products of combustion, means for directing a jet of air at a high velocity into the offtake in contact with the products of combustion and thence into the combustion space, means for diverting a part of the products of combustion from the offtake and introducing them separately into the combustion space, and means for introducing fuel into the diverted products of combustion before their entry into the combustion space.

10. A furnace having a combustion space, an offtake for the products of combustion, means for directing a stream of air at high velocity in contact with the products of combustion, whereby the air is heated and a portion of the products of combustion diverted, means for separating the major portion of the air from the diverted products of combustion and leading the air and products of combustion separately into the combustion space, and means for introducing finely divided fuel into the diverted products of combustion.

11. A furnace having a combustion space, an offtake for the products of combustion at one end of the combustion space, a passage connecting the offtake with the other end of the combustion space, means for introducing a stream of air at high velocity through the offtake into said passage, whereby the air is heated and a portion of the products of combustion are diverted into the passage, means in the passage adjacent the opening into the combustion space for dividing the major portion of the air from the products of combustion and causing the air and products of combustion to enter the combustion space in separate streams, and means for introducing finely divided fuel into the stream of products of combustion to be carried into the combustion space thereby.

12. A furnace having a combustion space, an offtake for the products of combustion at one end, a passage leading over the top of the combustion space and affording communication between the offtake and the com-

bustion space, means for directing a stream of air at high velocity through the offtake and into said passage in a direction to impinge on the top of said combustion space whereby said top is cooled, and means in said passage adjacent its opening into the combustion space adapted to divide the major portion of the air from the products of combustion and lead the air into the combustion space below the point of entry therein of the products of combustion, and means to introduce finely divided fuel into the separated products of combustion prior to the entry thereof into the combustion space.

13. A furnace having a combustion space, an offtake for the products of combustion at one end, a passage leading over the top of the combustion space and affording communication between the offtake and the com-

bustion space, means for directing a stream of air at high velocity through the offtake and into said passage in a direction to impinge on the top of said combustion space whereby said top is cooled, a partition dividing said passage into two parts adjacent its opening into said combustion space and an adjustable baffle adapted to effect a separation of the major portion of the air from the products of combustion and direct it to one side of said partition and to direct the products of combustion to the other side of said partition, and means to introduce finely divided fuel into the separated products of combustion.

In testimony of which invention, I have 35 hereunto set my hand, at Pittsburgh, Penna., on this 21st day of May, 1923.

KARL A. SODERSTROM.
